UNITED STATES PATENT OFFICE.

JOHN H. CARTER, OF KEOUK, IOWA, ASSIGNOR OF ONE-HALF TO FRANK A. WHITNEY, OF SAME PLACE.

LETTER-BOX.

SPECIFICATION forming part of Letters Patent No. 290,532, dated December 18, 1883.

Application filed February 15, 1883. (No model.)

To all whom it may concern:

Be it known that I, JOHN H. CARTER, of Keokuk, in the county of Lee and State of Iowa, have invented a new and Improved Letter-Box, of which the following is a full, clear, and exact description.

My invention relates to that class of mail-boxes that are adapted to be attached to the doors of dwelling-houses, into which the mail-carriers may drop the mail.

Reference is to be had to the accompanying drawings, forming part of this specification, in which similar letters of reference indicate corresponding parts in all the figures.

15 Figure 1 is a perspective view of my new and improved mail-box as it appears when closed. Fig. 2 is a vertical sectional elevation of the box as it appears when open, and Fig. 3 is an elevation of the bottom of the box.

20 A represents the main part of the box, attached by any suitable means to the outside of the door F. The outer edges of the side wall a a of this main part A are beveled off or inclined, as shown at a' a'.

25 B is the cover or closing part of the box, which is pivoted to the main part A upon the rod b, upon which it is adapted to rock. The side walls c c of this closing part B fit outside of the side walls a a of the main part 30 A, while the end pieces, c' c', thereof fit between them, as shown in Figs. 2 and 3. When the upper end of the part B is forced forward by the spring f, for closing the box, the upper portion of the outer wall, c', of the part B 35 will rest against the inclined edges a' a' of the main part A, and cause the upper wall, c', to close the upper end of the box A, as shown in Fig. 1, while the lower portion of the said wall c' will stand away from the straight portion a' a' of the walls a a, as shown clearly in dotted lines in Fig. 2; but the lower wall, c', of the closing part B is of such size, relative 40 to the bottom a' of the main part A, as to still close the bottom of the box. For opening the box, the upper portion of the cover or closing part B is to be drawn outward by means of the ring d, which will turn the part B on the rod b, so that the lower portion of the cover B will stand against the straight

portion a' a' of the wall a a, and its upper 50 portion away from the inclined portions a' a', as shown clearly in full lines in Fig. 2, thus causing the upper wall, c', to open the upper end of the main portion A, for depositing mail in and removing it from the box. The turning of the closing portion B upon the rod b in opening the box will be against the action of the spring f, which will automatically close the box as soon as the ring d is released.

55 The spring f may be arranged in various 60 positions to accomplish the automatic closing of the box; but I prefer to place it upon the rod g, which is attached to the closing part B below the pivot b, and passes thence through the back of the main portion A and through 65 the door F, and this rod has the alarm-bell h attached to its inner end, as shown in Fig. 2, so that the rod not only serves to apply the action of the spring f for closing the box, but at the same time serves to give the alarm 70 when the mail is deposited. Constructed in this manner, it will be seen that the box is cheap and simple and convenient for the mail-carrier, as no time will be required in closing the box.

75 The box may be made of sheet metal or wood, or the two combined, cast-iron, brass, or any other suitable metal; and the box may have a lock attachment so placed that the box 80 may be opened far enough by the carrier to deposit mail, but not far enough to allow mail to be taken out until it is unlocked, and the locking may be by a simple hasp and padlock, chain and lock, or any other suitable means; and, instead of having a separate alarm-bell, the rod g might be attached by a wire to the door-bell, and instead of making the bottom pieces, c' a', square, as shown, they may be concaved or dished, so as to fit each other, the curvature being struck from the pivot of 85 the closing portion B.

Having thus described my invention, what I claim as new, and desire to secure by Letters Patent, is—

90 1. In a mail-box, the part A, having the 95 side walls a a beveled at a' and straight at a', in combination with a pivoted part, B, having side walls c, fitting on the outside of walls a, end

walls, $c' c^2$, fitting between the walls $a' a$, and the wall c^3 , resting on the inclines a' , as shown and described.

2. The combination, with the parts A B, of 5 the rod g , attached to part B, passing across and through part A, the door F, provided with an opening for the passage of said rod, and the alarm h , connected with the end of said rod, whereby the same spring may simultaneously close the door and sound the alarm, as described.

3. The main portion A of the box, having the inclined outer edges, $a' a'$, and bottom a^3 , in combination with the closing portion B, having the end pieces, $c' c^2$, pivoted to the 15 main part A upon the rod b , substantially as described.

JOHN H. CARTER.
